UNITED STATES PATENT OFFICE.

GEORGE E. KING, OF NEWTON, MASSACHUSETTS, ASSIGNOR TO THE GAME-WELL FIRE ALARM TELEGRAPH CO., OF NEW YORK, N. Y.

TIME-STAMP.

SPECIFICATION forming part of Letters Patent No. 671,342, dated April 2, 1901.

Application filed January 30, 1900. Serial No. 3,363. (No model.)

To all whom it may concern:

Be it known that I, GEORGE E. KING, of Newton, county of Middlesex, and State of Massachusetts, have invented an Improvement in Time-Stamp, of which the following description, in connection with the accompanying drawings, is a specification, like characters on the drawings representing like parts.

This invention has for its object to improve and simplify the construction of time and date printing stamps adapted to be operated by an electromagnet to record the time and date on a strip of paper.

In the time and date printing stamp embodying this invention the time and date printing devices are made as rings or disks turning on vertical axes, so that all of their printing characters shall be disposed in the same horizontal plane. Some of the printing devices are adapted to be operated by a spring-impelled train, and others are adapted to be operated by hand. The platen by which the paper is pressed up against the printing devices is adapted to be raised by an electromagnet assisted by a spring, yet means are also provided for operating said platen by hand. The platen is supported in such manner that it always occupies approximately a horizontal position and also always occupies a predetermined position with relation to the printing devices, and it is so constructed that only certain portions of the printing devices will be comprehended within the boundaries of its contacting or engaging surface. A paper-support is located beneath the printing devices over which the paper travels, and in order that a free and unobstructed passage may be provided for the paper said paper-support is provided with a recess into which the platen recedes when in its lowermost position. The printing devices and operating devices therefor are supported by a frame which is independently removable from the main frame of the instrument, so that in case repairs are necessary said parts may be removed in assembled condition without disturbing any of the other parts of the instrument. A dial is provided at the top of the instrument over which travel suitable hands moving in unison with the time-printing devices to thereby

visually indicate the position of said time-printing device, and means are also provided whereby the position of the date-printing devices are also visually indicated. The inking-ribbon is contained in a ribbon-holder consisting of a sliding frame which is suitably supported in guideways in proper position for use, and said frame is adapted to be withdrawn without disturbing any of the other parts of the instrument.

Figure 1 shows in side elevation a time and date printing stamp embodying this invention. Fig. 2 is a front elevation of the same. Fig. 3 is an under side view of the same. Fig. 4 is a plan view of the same. Fig. 5 is an enlarged vertical section, full size, of the time and date printing stamp, taken on the dotted line xx , Fig. 2, the platen being shown in elevated position. Fig. 6 is an enlarged vertical section, full size, of the time and date printing stamp, taken on the dotted line yy , Fig. 1, the platen being shown in elevated position. Figs. 7, 8, 9, and 10 are details to be referred to. Fig. 11 is an under side view of the time and date printing devices, and Figs. 12 and 13 are details to be referred to.

The base a of the machine is made quadrangular and has erected upon it two upright side plates $a' a'$, made substantially alike and located one at each side of the base. The base a is made as a shell, having an upright marginal flange which serves as a support and having a horizontal top piece which is essentially cut away. Two electromagnetic coils $b b$ are disposed in the cut-away portion of the base a and occupy a horizontal position, and said coils are secured rigidly to a heel-piece b' , which is in turn secured by screws 2 to the top of a supporting-plate b^2 , which is secured to the under side of the base a by screws 3 or otherwise.

The supporting-plate b^2 is made T-shaped, as shown in Fig. 3, and the extremities of two of its arms are attached rigidly to the base a , and its other arm extends along between the two coils $b b$. The two coils $b b$ of the electromagnet are thus supported by the base.

A block b^4 of insulating material is secured to the under side of the supporting-plate b^2 , 100

to the under side of which two contact-plates $b^5 b^5$ are secured, to which the leading-in wires are connected.

The armature b^7 of the electromagnet b is secured to a lever b^8 , fastened to a pivot rod or shaft b^9 , having its bearings in a pair of ears $b^{10} b^{10}$, which are secured to the base by screws 4 or otherwise.

The armature b^7 is retracted by the gravitating action of the parts supported by it, as will be described, and attracted by the electromagnet b ; but its attractive movement is assisted by a spring b^{12} , which is coiled around the pivot-bar b^9 and which has two projecting ends $b^{13} b^{14}$, one of which, as b^{13} , is attached to a vertically-adjustable post b^{15} , and the other of which, as b^{14} , rests upon or against a pin b^{16} , and said end b^{14} is itself formed with a coil b^{17} intermediate its length, and said end b^{14} is disposed so as to engage the lever b^8 at the proper time to assist in attracting the armature. The tendency of this spring is to assist in moving the armature toward the poles of the electromagnet and is designed to act at the beginning of its attractive movement and during a part of said movement and to cease acting just before the armature arrives in its attracted position, and the tension or force of said spring is adjusted by turning the post b^{15} . The spring b^{12} thus assists the electromagnet in moving the armature and parts connected with it when said armature is occupying a position in the weakest part of the magnetic field, and is thus unlike the ordinary retractile springs usually used and which I am aware is old.

The platen c is made circular, as a disk, and is herein adapted to at all times occupy a true horizontal position, and to accomplish this result it is connected universally or by a universal joint with its support c' .

As herein shown, the platen c has formed on its under side a spherical projection or boss c^2 , which is contained in a correspondingly-shaped recess formed in the extremity of the arm c' , said recess serving as a seat for said boss and said arm serving as a support for the platen. The arm c' is secured to a horizontal pivot rod or bar c^3 , having its bearings in the side plates $a' a'$. A rod or bar c^4 is connected to the spherical boss c^2 on the under side of the platen c , which extends down through a hole c^5 , provided for it in the extremity of the supporting-arm c' , and thence passes down between the two coils $b b$ of the electromagnet, and at the lower end of said rod or bar c^4 a quadrangular or other-shaped extension c^6 is secured, which passes down through a correspondingly-shaped hole in a plate c^7 , which is secured to the supporting-plate b^2 . The rod or bar c^4 is free to move up and down in the hole in the plate c^7 , but will be held by said plate in a vertical position at all times, so that the platen will at all times be held in an approximately horizontal position regardless of the position of the supporting-arm c' , bearing said platen, and con-

sequently said rod or bar serves as a guide-rod for said platen. The extension c^6 , being of any other shape than round and sliding in a correspondingly-shaped hole in the plate c^7 , also keeps the rod or bar from turning on its axis, and consequently the platen will at all times occupy the same relative position to the printing device (to be described) with which it co-operates. Thus it will be seen that the platen is not only guided and held in true horizontal position at all times, but also is held in a predetermined position at all times relative to the printing device. The hole c^5 , which is provided at the extremity of the supporting-arm c' , will be made of suitable size and shape to provide for the rod or bar c^4 moving freely as the supporting-arm c' is moved on its pivot. As a means of moving the supporting-arm c' on its pivot, to thereby move the platen up against the printing device, a link c^{10} is loosely connected at one end to said supporting-arm c' , its opposite end being connected to the upper end of the armature-lever b^8 , and said link c^{10} is connected with said armature-lever in such manner as to form a toggle which will be straightened more or less when the armature b^7 is attracted. I find that by employing a toggle connection of this character the platen may be raised forcibly against the printing device in order that a good impression may be made upon the paper.

It is desirable to provide means for adjusting the platen more or less, and to accomplish this result the lower end of the link c^{10} , which is connected to the upper end of the armature-lever b^8 , has a hole through it which receives the eccentrically-disposed shank c^{15} (see Fig. 7) of a pin which passes through the upper end of said armature-lever, and said pin has opposite end portions $c^{16} c^{17}$, made or formed concentrically to its axis, which turn in holes provided at the upper end of said armature-lever b^8 , so that by turning said pin its eccentric shank portion c^{15} will move the link c^{10} to different elevations and correspondingly move the platen.

It is sometimes desirable to operate the platen by hand instead of by the electromagnet b , and, as herein shown, a spring-pressed handpiece d is provided, which is mounted in the frame opposite the armature-lever b^8 , which is adapted to be pressed inward by hand to engage and move said armature-lever the same as it is moved by the electromagnet.

The electromagnet b , its armature, and armature-lever are contained in a box-like structure on the base a , and the side plates $a' a'$ are formed to present two sides of said structure, as shown in Figs. 1, 2, and 6, and removable plates d^5, d^6 , and d^7 form the two ends and the top thereof, and a slot d^8 is provided in the top plate d^7 for the link d^{10} and rod c^4 , both of which pass through it.

The paper to be printed upon is in the form of a strip, and it passes beneath the printing

device and above the platen *c*, and to support the strip of paper in such position a paper-support is provided, which consists of a curved plate *e*, made of suitable length to extend from side to side of the machine and of suitable width to properly support the strip of paper, and said curved plate is rabbed at each end to form a seat *e'*, (see Fig. 6,) adapted to rest upon the upper edge of the side plates *a' a'* and to form a shoulder or lip *e''*, which extends down inside of said side plates, thereby furnishing a good and sufficient support for the plate. The paper-support is thus adapted to be placed in position on the side plates in such manner that it may be removed easily whenever desired. The paper-support *e* has a hole through it, substantially midway its length and width, of suitable size and shape to receive the platen *c*, so that when said platen occupies its lowermost position its top surface will be substantially flush with the plate, as shown in dotted lines, Fig. 1. The strip of paper is therefore not obstructed in any way, yet overlying the platen, as it does, may be readily raised by the platen and pressed into firm contact with the printing device.

The printing devices comprise, essentially, time and date printing devices adapted to print the time—*i. e.*, hour and minute—also post and ante meridian indications, also the month and day of the month, and also the year, and said printing devices are all supported by a removable frame, so that in case any repairs are necessary they may be removed in assembled condition without disturbing any of the other parts of the machine.

The time-printing devices are adapted to be operated by any suitable motor mechanism, and the date and other printing devices are adapted to be operated by hand.

f f' represent two horizontally-disposed plates which are rigidly secured together by posts *f''*, four such posts being herein employed for the purpose, and said plates *f f'* and posts constitute the essential parts of the frame which supports the printing devices. The top plate *f* is made circular in shape and the bottom plate *f'* is made substantially rectangular in shape. The circular top plate *f* rests upon and is adapted to be secured by screws or otherwise to inwardly-projecting flanges *f''*, provided within a circular opening *f''*, formed in a plate *f''*, which is made quadrangular or any other suitable shape and which is mounted on top of the upright side plates *a' a'* and secured thereto by thumb-screws *f''* or otherwise. The plate *f''* is thus detachably connected to the side plates *a' a'* and may be readily removed. There are herein shown three inwardly-projecting flanges *f''* within the circular opening *f''* in said plate *f''* (see Fig. 12) so disposed as to properly support the plate *f*, yet at the same time leave an opening of suitable shape for the unobstructed passage through it of the substantially rectangular bottom plate *f'*, so

that even though said plate *f''* should not be detached from the side plates *a' a'* the top plate *f* and the bottom plate *f'*, which are rigidly connected together and the parts supported by them, can be removed in assembled condition. It will, however, be understood that as the top plate *f* is secured to the flanges *f''* of said plate *f''* said top plate *f* and all the parts connected with it may be removed with said plate *f''*, if desired.

The time-printing devices comprise, essentially, a stationary ring *i*, fitting a recess in the under side of the bottom plate *f'*, about midway its length and width, and secured to said bottom plate, said ring *i* having formed or provided on its under face characters representing the hours and minutes and resembling an ordinary clock-face, and movable members or hands are provided which are adapted to be moved relatively to said stationary ring *i* to indicate the hours and minutes. Two such movable members or hands are provided, as *i' i''*, one of which, as *i''*, is made as a ring formed on the lower end of a tubular shaft and fitted into and adapted to revolve in a recess formed within said stationary ring *i*, and the other of which, as *i'*, is made as a circular disk fitted into and adapted to revolve in a recess within said ring *i''*. The ring *i''* has formed on its under side a single triangular projection, (see Fig. 11,) and the disk *i'* has formed on its under side a projection like unto an arrow, and as said ring and disk move relatively to the stationary ring *i* the triangular projection and arrow will point to the correct hour and minute. The arrow on the disk *i''* is supposed to be the minute-hand and the triangular projection on the ring *i'* is supposed to be the hour-hand, and the parts bearing them will travel accordingly.

By arranging the stationary ring *i* and ring *i'* and disk *i''* in relative positions, as shown, it will be seen that the impression made on the strip of paper will be like unto an ordinary clock-dial.

Any suitable means may be provided for rotating the ring *i'* and disk *i''* relative to each other and to the stationary ring *i* so far as my invention is concerned, although herein the disk *i'* is represented as connected to a centrally-disposed main shaft or arbor *n*, so as to turn with it, and the ring *i''* connected with said main shaft or arbor by gearing like unto an ordinary clock, said gearing being herein represented as a toothed wheel *n'*, connected with the ring *i''* and sleeved onto the main shaft *n*, which engages a pinion *n''*, connected with a toothed wheel *n'''*, which engages a pinion *n''*, secured to said main shaft or arbor *n*.

As a means of connecting the disk *i'* and ring *i''* with the parts supporting them, so that they will be positively revolved, yet will be undisturbed by the shock incident to a sudden blow of the platen, I have formed the disk *i'* at the lower end of a tubular shaft,

which is provided with a pair of upright arms i^{10} , which frictionally embrace a projection i^{12} on the lower end of the main shaft n , and said disk i' extends beneath a shoulder formed on 5 the ring i^2 , which latter is formed with an external shoulder adapted to abut against a shoulder formed on the stationary ring i , and said ring i^2 is formed at the lower end of a tubular shaft i^4 , which incloses the arms $i^{10} i^{10}$ 10 and which has formed at its upper end arms i^5 , which enter recesses in a disk i^6 , secured to a sleeve i^7 , mounted on the main shaft n , and to which the toothed gear n' is connected. The main shaft or arbor n will be driven by 15 any suitable clockwork, and as my invention does not include any particular construction of clockwork I have omitted to illustrate the same. The main shaft or arbor n passes up through plates $n^5 n^6$, which form the upper 20 and under plates for the clockwork or motor mechanism, (not shown,) and said shaft also passes up through the top plate f and through a dial-plate g , which is located above the plate f and which is suitably supported.

25 The dial-plate g will have on its top face characters like unto the face of a clock, and the main shaft or arbor n , which projects up through it, will bear two hands $g' g^2$, which travel over said dial in unison with the disk 30 i' and ring i^2 . One of said hands, as g' , is connected directly with said main shaft or arbor, and thereby turns in unison with the disk i' , and the other hand is secured to a sleeve g^3 , bearing a toothed wheel g^4 , which 35 engages a pinion g^5 , connected with a toothed wheel g^6 , which engages a pinion g^7 , secured to said main shaft or arbor, and thereby turns in unison with the ring i^2 . Thus it will be seen that as the time-printing devices are continuously 40 operated by the motor (not shown) the hands $g' g^2$ will also be operated to at all times visually indicate the position of the time-printing device.

On the under side of the bottom plate f' a 45 boss j' is formed adjacent the stationary ring i , (see Fig. 11,) on which the character "M" is formed, and on the other side of said stationary ring i a disk j' is provided, which is set in a recess in the under side of said bottom 50 plate f' and which is adapted to be revolved, and on the under face of said disk j' the letters "A" and "P" are formed, so that when the impression is made on the strip of paper the letters "A. M." and "P. M." may be 55 struck. The disk j' is adapted to be turned half a revolution each time it is operated, so as to bring the letter "A" or the letter "P" in proper position to print upon the paper, and to thus revolve the disk it is attached to 60 a shaft j^2 , (see Fig. 9,) which is connected with the hub j^3 on the under side of a barrel j^4 , mounted on a stud j^5 , and a spring j^6 is contained in said barrel j^4 , one end of which is connected to the barrel and the other end 65 to a ratchet-wheel j^7 , also mounted on said stud. A pawl j^8 engages the teeth of said ratchet-wheel j^7 , which prevents backward

movement thereof, and a projection j^9 on the hub of the pinion j^{10} is adapted to engage said ratchet-wheel and turn it one tooth during 70 each revolution of said pinion n' , so that as the ratchet-wheel is thus turned the spring contained in the barrel j^3 will be wound. The barrel is held at rest at intervals in either one of two positions by two pawls $k k'$, engaging a projection k^2 on the barrel, and means are provided for disengaging either one of said pawls at a predetermined time, and when disengaged the barrel will turn one-half of a revolution or until its projection k^2 80 engages the other pawl. To disengage either one of the pawls at a predetermined time, a cam-groove k^4 is formed on the face of the ratchet-wheel j^7 , which engages a pin on the pawl. Thus it will be seen that the disk j' , 85 bearing the letters "A" and "P," will be turned half a revolution at regular intervals to bring either one of the letters into proper position to print upon the paper, and such result is accomplished by the spring-impelled 90 train, by means of which the time-printing devices are operated. Other disks l and m are secured to the under side of the bottom plate f' , which are adapted to be turned by hand whenever desired, the disk l , as herein 95 shown, bearing the figures "18" and "19" and the disk m , as herein shown, bearing the figures "'99, '00, '01, '02," and said disks when set in proper position will print any year upon the paper.

To print the month and the day of the month, two like disks o and p are provided, which are fitted to turn in recesses formed in the under side of the bottom plate f' , and each disk is attached to the lower end of an 105 upright shaft $o' p'$, which projects up through the plates n^5 , n^6 , and f , and each shaft has its upper end squared, as at $o^2 p^2$, and said squared ends are accessible through openings $o^3 p^3$, formed in the dial-plate g , so that they 110 may be turned by a suitable key whenever desired. The disk o will have formed on its under side or face letters to indicate the months of the year, and the disk p will have formed on its under side or face figures to 115 indicate the days of the month. Disks $o^4 p^4$ are secured to the shafts $o' p'$ near their upper ends, which have their bearings in holes in the plate f and are disposed above said plate f , and therefore just beneath the plate 120 g , and said disks $o^4 p^4$ have on their upper sides or faces letters and figures indicating the months and days of the months, like the disks o and p . In the dial-plate g holes $o^5 p^5$ are formed or provided, beneath which the 125 disks $o^4 p^4$ travel, and through said holes $o^5 p^5$ the month and day of the month may be observed. By employing the disks o^4 and p^4 it will be seen that the disks o and p may be moved to occupy proper positions to print 130 upon the paper, which greatly reduces the attention required to be given to the instrument. All of the time and date printing devices thus occupy a position substantially

flush with the under side of the bottom plate f or in a horizontal plane, and the platen c rises in a horizontal plane, and thus presses the paper against the printing devices, the 5 inking-ribbon being interposed between them, as shown. In order that only such portions of the printing devices shall print upon the paper as is required, the platen c is made of metal and its upper surface is cut away, as 10 shown in Fig. 8, and said cut-away portion is filled with a rubber pad c^20 , made of suitable shape to fit, and, as shown, said pad has a central portion for the time-printing devices and several arms or projections (six being 15 herein shown) for the other printing devices, there being two arms or projections for the "A. M." and "P. M.," two arms for the year, one arm for the month, and one arm for the day of the month, and as the platen is raised 20 only these portions of the printing devices will be printed upon the paper.

The plate f^5 is formed or provided with an upwardly-extended rim or flange f^{20} , upon which a glass plate f^{21} may be placed, with a 25 suitable spring interposed between it and the rim, and a collar f^{22} is adapted to be placed on said rim f^{20} , which holds the glass plate in position. A cylinder t is provided having at its upper end an outwardly-projecting rim or 30 flange t' , which overlies the said plates a' a' and is fitted into recesses formed therein, (see Fig. 6,) so that said cylinder t is thus properly supported, and said cylinder is of suitable size to surround or inclose the clockwork 35 or motor mechanism and other parts contained between the top plate f and bottom plate f' , and said cylinder is made circular and has a circular opening at the top of substantially the same size as the circular plate f , and at the bottom it has a substantially 40 rectangular opening of approximately the same size and shape as the bottom plate f' . The bottom of the cylinder t is therefore partially closed—that is to say, it has an oblong 45 opening extending across it diametrically from side to side, but at each side of said opening is closed, and at each side of said opening, along the closed portions of the bottom of the cylinder, a recess is formed or provided for the inking-ribbon holder.

Rolls w w' are herein shown as adapted to receive the inking-ribbon, and they are made as rods or shafts having thumb-nuts w^3 at their outer ends, by means of which they may 55 be turned by hand as desired, and the ribbon passes from one to the other rod or shaft, as shown in Fig. 6, directly along beneath the printing device. The rods or shafts w w' have their bearings in sliding drawers w^3 w^4 , 60 which are made substantially alike. The drawer w^3 is formed with a top wall, two longitudinal side walls, and two end walls, being open at the bottom, and said drawer has on one side of it at the top a laterally-projecting rib or flange w^5 , which enters a correspondingly-shaped recess in the bottom of the 65 cylinder. The rod or shaft w' has its bear-

ings in the end walls of the drawer, and the thumb-nut is disposed outside of the front end wall. The two drawers w^3 w^4 are rigidly 70 connected together, so that they may be withdrawn together, and, as herein shown, a strap w^6 is attached at its opposite ends to the rear ends of said drawers at the bottoms thereof, and a strap w^7 is attached at its opposite ends 75 to the front end walls of said drawers. When the drawers are in position to hold the inking-rolls in proper position for use, the front strap w^7 will bear against the cylinder t , as shown in Fig. 5, and as said drawers are withdrawn the strap w^6 will pass beneath the bottom plate f^7 . In Figs. 10 and 13 the drawers bearing the inking-rolls are shown as partially withdrawn from the support bearing them. The drawers may be removed by withdrawing them at any time and also may be removed with the cylinder t whenever desired.

I claim—

1. In a time-stamp, the combination of a printing device, a platen, a support for said platen, an electromagnet and armature, a pivoted armature-lever, with which the support for said platen is connected, which is adapted to be moved into its retracted position by the gravitating action of said platen and its support, and the spring b^{12} in the path of said armature-lever but not connected thereto, which serves as a yielding back-stop for said armature-lever and is adapted to be compressed by the gravitating action of said platen and its support, and thereby constitute a supplementary actuator working conjunctively with the said electromagnet in raising said platen when said electromagnet is energized and serves as a main actuator, substantially as described.

2. In a time-stamp, the combination of a printing device, a platen, a pivoted supporting-arm to which said platen is connected by a universal joint, a guide-rod depending from 110 said platen and guide therefor whereby said platen is held in approximately horizontal position as the supporting-arm is moved on its pivot, substantially as described.

3. In a time-stamp, the combination of a printing device, a platen, a pivoted supporting-arm to which said platen is connected by a universal joint, a guide-rod depending from said platen and guide therefor constructed and arranged to hold said platen in approximately horizontal position and also in a pre-determined position relative to the printing device as the supporting-arm is moved on its pivot, substantially as described.

4. In a time-stamp, the combination of a printing device, a platen, a pivoted supporting-arm for said platen, a spherical boss on the under side of said platen, a seat formed in the supporting-arm for said boss, a guide-rod depending from said boss which passes 130 freely through a hole in said arm and enters a hole in a fixed plate, substantially as described.

5. In a time-stamp, the combination of a

printing device, a platen, a pivoted supporting-arm for said platen, a spherical boss on the under side of said platen, a seat formed in the supporting-arm for said boss, a guide-
5 rod depending from said boss which passes freely through a hole in said arm, and has a guiding portion other than round, and a fixed plate having a hole shaped to correspond to the shape of said guiding portion, in which
10 said guiding portion is free to slide, substantially as described.

6. In a time-stamp, a printing device, a platen, a pivoted supporting-arm bearing said platen, a toggle-lever connected with said
15 supporting-arm, an armature borne by one member of said toggle-lever, an electromagnet, and the spring ^{b12} in the path of said armature-bearing toggle-lever, but not connected thereto, which serves as a yielding
20 back-stop for said armature toggle-lever and is adapted to be compressed by the gravitating action of said toggle-lever, platen, and its support, thereby constituting a supplementary actuator working conjunctively with
25 said electromagnet in raising said platen when said electromagnet is energized and serves as a main actuator, substantially as described.

7. In a time-stamp, the combination of an
30 electromagnet, its armature, a platen connected with and operated by said armature, contact-plates to which the leading-in wires to said electromagnet are connected, a main frame supporting all of the aforesaid parts, a
35 time-printing device, a motor for operating it, and an independent frame supporting said time-printing device and motor which is re-

movably connected with said main frame, whereby said parts may be removed in assembled condition, substantially as described. 40

8. In a time-stamp, the combination of a main frame comprising a base, and upright side plates, an electromagnet its armature and a pivoted armature-lever supported by said base, a platen, a supporting-arm bearing 45 it pivoted to said side plates, intermediate connections between said pivoted supporting-arm and armature-lever, a time-printing device, a motor for operating it, and an independent frame supporting said time-printing device and motor which is removably connected with said side plates, whereby said parts may be removed in assembled condition, substantially as described.

9. In a time-stamp, a date-printing device 55 comprising a ring having on its lower face a number of reversed characters, an operating-shaft for said ring having a squared end, a disk secured to said shaft having on its upper face normally-disposed characters corresponding in number and location to the characters on the ring, a plate having a hole through it through which the squared end of the shaft is accessible and also having a hole through it beneath which any one of the 60 characters on the disk may be brought to view, substantially as described.

In testimony whereof I have signed my name to this specification in the presence of two subscribing witnesses.

GEO. E. KING.

Witnesses:

B. J. NOYES,
J. L. HUTCHINSON.
